UNITED STATES PATENT OFFICE.

HARRY E. TUNNELL, OF NEW YORK, N. Y., ASSIGNOR TO FIRE GUN MANUFACTURING COMPANY, INC., OF NEW YORK, N. Y., A CORPORATION OF NEW YORK.

LOCKING DEVICE FOR PUMP HANDLES.

Application filed April 7, 1919. Serial No. 288,184.

To all whom it may concern:

Be it known that I, HARRY E. TUNNELL, a citizen of the United States, and resident of the borough of Manhattan, city, county, and State of New York, have invented certain new and useful Improvements in Locking Devices for Pump Handles, of which the following is a specification.

My invention relates to devices for locking pump-handles in their inoperative positions, and is particularly adapted for use in connection with fire-extinguishers or like devices in which the pump serves to discharge or expel liquid from a container.

The object of my invention is to provide a simple construction for normally locking the pump handle in its inoperative position, yet allowing its ready disengagement when it is desired to operate the pump. Preferably, I so construct the appliance that a mere longitudinal movement of the handle inwardly will not only lock the handle against longitudinal movement, but will also operate a device to close the outlet through which the liquid is ejected during the operation of the pump, while an outward movement of the handle, or of the locking device, will release the pump piston for operation and at the same time free the said outlet.

Without desiring to restrict myself to the specific construction shown, I will now describe a preferred embodiment of my invention with reference to the accompanying drawings, in which Fig. 1 is a partial longitudinal section of a fire-extinguisher provided with my improvement, the handle of the pump being shown in the locked position; Fig. 2 is a similar view showing the locking device in the released position; Fig. 3 is a section substantially on line 3—3 of Fig. 1; Fig. 4 is a side elevation of the handle; and Fig. 5 is a cross section on line 5—5 of Fig. 1.

In the drawings, I have shown the improved locking device in connection with the container having a head 10 and a shell or body 10', said head being provided with an opening having a flange 10" adjacent thereto, against which is seated a tubular casing 11 engaging the pump barrel 12 which is stationary in the container. The casing 11 also has a channel 11' communicating with a pipe 13 through which the liquid or fluid is caused to travel by the

reciprocation of the pump piston. In the outer portion of the casing 11 is contained a box or holder 14 for packing material 15, the details of this packing or stuffing-box construction, with the channels 11" and 14' 60 for the inlet of air and return of liquid being described more fully and claimed in another application for Letters Patent filed by me in the United States Patent Office on January 18, 1919, Serial No. 271,830. 65 Through the said packing extends the piston rod 16 of the pump, said rod also passing through a gland 17 threaded into the box 14. The projecting portion of the gland 17 fits into a tubular member 18 provided 70 with a flange 18' seated on the outside of the flange 10" and soldered or otherwise secured thereto. This member, which forms part of the locking device, has an annular recess 18" in which are adapted to be seated 75 the locking balls 19. These balls also engage sockets having vertical walls 20', that is to say, walls parallel to the path along which the piston rod 16 reciprocates, said sockets being formed on the inner surface 80 of an outwardly-contracted member 20 rigid or integral with the lower portion 21 of the pump handle. The piston rod 16 is secured, as by a screw connection 16', to a member 22 which flares correspondingly to 85 the member 20, said member 22 being made with a shank or stem 22' riveted or otherwise secured to the outer handle portion 23. The balls 19 further engage a flange 22" and socket walls 22* on the member 22. The 90 handle portion 21 with the member 20 is adapted to slide lengthwise on the shank or stem 22', and a spring 23' coiled on said stem between the two handle portions 21, 23 tends to separate said handle portions, 95 as in the position illustrated by Fig. 1. Both handle portions are oblong or oval, and one of them, as 21, is guided for sliding movement in the other.

At the other or lower end of the container 100 I have shown a head 10* suitably connected with an outlet casing 24 which has secured thereto a nozzle 25 projecting to the outside of the container and provided with a passage 25' through which the fluid is ejected. 105 The passage 25' is connected with a chamber 25" separated by an annular wall from an annular chamber 25* which is in permanent communication, through apertures 25a, with an annular chamber 24', and through a port 110

24", with a delivery passage 26 through which the fluid passes to said chamber 24". The casing 24 is also provided with a perforated partition 24^a and with a port 24^b located on the same side of said partition as the pump barrel 12. On the other side of said partition is formed a chamber 24* in which a valve member 27 is adapted to move toward and from the nozzle 25, said valve member when in the closing position (as shown) being seated on two annular ridges of the nozzle member 25 and cutting off the communication of the chamber 25* both with the chamber 25" and with the chamber 24*. 15 A spring 28 tends to open said valve, which is also engaged by a second, stronger spring 29 holding the valve member tightly against its seat when the handle is pushed fully inward. The spring 29 also bears against a 20 collar 30' on a sliding member 30 interposed between the valve member and the inner end of the piston rod 16, said sliding member being guided in the partition 24^a and adapted to be engaged, and forced toward 25 the outlet nozzle, by the end of the piston rod 16 projecting beyond the piston 16". The details of the valve mechanism at the nozzle are not claimed by me in this application, although they were likewise invented 30 by me; it will be obvious that the result of sealing the outlet by merely pushing the handle fully inward, may be obtained with other outlet valve constructions than the one illustrated. I have not illustrated herein 35 certain valves connected with the pipe 13, passage 26 and with the port 24^b, to secure a proper operation of the pump as the piston 16" reciprocates; these parts may be constructed in any suitable manner, for instance as disclosed in my pending application above referred to.

When the apparatus is not in use, the parts are in the position Figs. 1 and 5, the balls 19 lie within the recess 18" of the member 18, the latter being stationary relatively to the pump barrel 12. The outer portions of these balls lie opposite the vertical socket walls 20', the spring 23' pressing the members 21, 20 down into the locking position, and as long as the part 20 is in this position, the balls 19 are unable to leave the recess 18". Thus, if with the parts in the position Fig. 1, an outward pull should be exerted on the handle portion 23 alone, this would cause the flange 22", which is rigidly connected with said handle portion 23, to exert pressure upwardly or outwardly on the balls 19, but as the member 20 at this time prevents the balls from leaving the recess 18", the outer portion of the member 18 (beyond the recess 18') will form a stop locking the said balls together with the member 22 and the handle portion 23, and consequently also the piston rod 16 and piston 16", against longitudinal outward move-

ment. At the same time, pushing the parts inward to the position shown in Figs. 1 and 5 also locks the valve member 27 in the sealing position, since the piston rod 16, which is locked as explained above, through its 70 action on the sliding member 30 and on the spring 29 presses the member 27 tightly against the two valve seats.

When it is desired to operate the pump, the user simply grasps the handle 21, 23, and 75 in the act of so doing necessarily brings the said two handle portions together by the pressure exerted by his fingers toward the thumb and the palm, thereby causing the portion 21 with the attached member 20 to 80 slide outwardly relatively to the handle portion 23 and attached member 22, 22', 22". The vertical socket walls 20' are thus brought out of alignment with the centers of the locking balls 19, so that the latter are no longer 85 restrained against movement away from the axis of the piston rod 16, the opening at the lower end of the member 20 flaring beyond said vertical walls, thereby affording room or play for such outward movement of the 90 balls 19. If then the entire handle together with the piston rod 16 is pulled outwardly, the flange 22" will cause the balls 19 to share this longitudinal movement, while the curved or inclined outer wall of the recess 95 18" will force the said balls away from the piston rod, thus releasing the handle from the locking action of the balls. The handle, piston rod 16, and piston 16' may thus be reciprocated freely to cause the fluid to be 100 expelled through the nozzle 25 in any well-known or approved manner. Fig. 2 shows the position of the parts just as the release of the locking balls 19 occurs.

When the pump is no longer used, the 105 handle will be pushed in fully, the balls 19, which always remain in the sockets 22*, pass over the outer end of the stationary member 18 into registry with the recess or groove 18", and when the handle is released, the 110 spring 23' will throw the member 20 and the locking balls 19 into the locking position illustrated by Figs. 1 and 5. When the operation of the pump begins, the valve member 27 is opened not only by the spring 115 28, but by the pressure of the liquid entering the chamber 25*. A washer 31 helps to prevent leakage when the handle is pushed in fully.

I claim as my invention:

1. A pump comprising a stationary member and a reciprocating member including a handle having two portions slidably relatively in the direction of the reciprocation, and co-operating locking elements connected 125 respectively with said stationary member and with one of said handle portions.

2. A pump comprising a stationary member and a reciprocating member including a handle having two portions one of which 130

is slidable relatively to the other in the direction of the path of reciprocation, a spring tending to separate said handle portions, and co-operating locking elements connected with said stationary member and said movable handle portion respectively, and brought to the releasing and locking positions respectively by a longitudinal movement of the reciprocating member in conjunction with a relative sliding movement of the movable handle portion toward or from the other handle portion respectively.

3. A pump comprising a stationary member including a barrel, a reciprocating member including a piston arranged to move in said barrel, a piston rod secured to said piston, a handle portion secured to said piston rod, another handle portion slidable lengthwise on the piston rod, and locking mechanism controlled by the movement of the last-named handle portion relatively to the first-named handle portion.

4. A pump comprising a stationary member and a reciprocating member having two portions movable relatively in the direction of said reciprocating movement, and a locking member adapted to co-operate with said stationary member and carried by one of said portions of the reciprocating member, said locking member being movable transversely relatively to both portions of the reciprocating member, the other portion of said reciprocating member projecting into the transverse path of the locking member and controlling the extent of its transverse movement.

5. A pump comprising a stationary member having a recess, and a reciprocating member having two relatively-movable portions and a ball carried by one of them and adapted for locking engagement with said stationary member at the recess thereof, the locking or release of said ball being controlled by the relative motion of the two portions of the reciprocating member.

6. A pump comprising a stationary member and a reciprocating member including a handle having two portions relatively slidable in the direction of reciprocation and in sliding engagement with one another, and locking elements connected respectively with one of said portions and with the stationary member, and controlled by the relative movement of said portions.

7. A pump comprising a stationary member and a reciprocating member having two relatively-movable portions one of which has a restraining surface, and a locking ball carried by the other portion of the reciprocating member and restrained or freed by said surface according to the relative position of said portions.

8. A pump comprising a stationary member having a recess, and a reciprocating member having two portions movable relatively in the direction of the reciprocating movement, a ball carried by one of said portions and movable thereon transversely into and out of said recess, such transverse movement of the ball being controlled by the relative longitudinal movement of the two portions of the reciprocating member.

9. A pump comprising a stationary member having a recess and including a barrel, a reciprocating member including a piston arranged to move in said barrel, a piston rod secured to said piston, a handle portion secured to said piston rod, a carrier likewise secured to said piston rod and provided with a seat, a ball on said seat, adapted for locking engagement with the stationary member at the recess thereof, another handle portion mounted to slide lengthwise on the piston rod and in sliding engagement with the first-named handle portion, said sliding handle portion being provided with a restraining surface which may be retracted to allow the ball to move out of locking engagement with the stationary member, and a spring tending to throw said sliding handle portion into a position in which its restraining surface will block the movement of said ball away from the axis of the piston rod.

10. A pump comprising a stationary member and a reciprocating member, the latter including a handle having two similar portions each projecting to both sides of the axis of said reciprocating member, said handle portions being relatively movable on both sides of said axis to bring them toward or from each other, and a locking device co-operating with said stationary member and controlled by the relative movement of the two handle portions.

In testimony whereof I have signed this specification.

HARRY E. TUNNELL.
